SNAP-IN CONNECTOR BLOCK

Douglas K. Rollow, Los Angeles, Calif., assignor,
by mesne assignments, to Lockheed Aircraft
Corporation, a corporation of California

Application July 31, 1943, Serial No. 496,881

6 Claims. (Cl. 173—334)

1

This invention relates to electrical equipment and relates more particularly to connector blocks. A general object of the invention is to provide a practical, dependable and inexpensive connector block for mechanically and electrically connecting electrical conductors.

Another object of the invention is to provide a connector block suitable for use in aircraft, automotive vehicles, electrical devices, machinery, etc., by means of which two or more wires or similar electrical conductors may be easily and quickly, electrically and mechanically connected.

Another object of the invention is to provide a connector block in which the conductors may be expeditiously connected and disconnected without the employment of any tools whatsoever. In employing the connector block, the wires are equipped with coupler tips or pins which are merely snapped into multiple coupler units in the block to be electrically and mechanically connected. The coupler tips are firmly and dependably held by the coupler units to maintain full electrical connection, but may be intentionally detached by a simple manual pull.

Another object of the invention is to provide a connector block in which the individual wires or conductors may be separately connected and disconnected without the necessity of removing or otherwise disturbing the coupler units or the other conductors. Two or more pairs of wires may be electrically and mechanically connected by the device of the invention and the individual wires may be separately handled without disturbing the other wires. This is a distinct advantage over the binding post type of connector block in which the disconnection or connection of a single wire often necessitates the detachment and subsequent re-attachment of several other wires.

Another object of the invention is to provide a connector block of the character referred to in which pluralities of sets or groups of two or more wires may each have their individual members or conductors maintained in electrical and mechanical connection, the several sets or groups remaining entirely distinct and electrically insulated one from the other.

Another object of the invention is to provide a connector block of the character referred to that may be supplied with as many multiple coupler units as required for a given installation. The multiple coupler units may be inserted in the block in the number and locations required for a given installation and may be easily shifted, replaced and increased or decreased in number at any time.

2

Another object of the invention is to provide a connector block that embodies a simple one piece block body which houses and fully protects the multiple couplers.

5 A further object of the invention is to provide a connector block in which the wires of any given group or set may all be brought into one side or into both sides of the block as required. The connector block of the invention provides for the connection of straight-through wires as well as branch leads or wires on one or both sides of the block.

10 A still further object of the invention is to provide a connector block of the character referred to that is simple and inexpensive to manufacture and easy to install and service.

15 Other objects and features of the invention will be made apparent by the following detailed description of typical preferred forms of the invention throughout which reference is made to the accompanying drawing in which,

Figure 1 is a plan view of a connector block of the invention with a portion of the cover broken away to expose the interior of the block;

20 Figure 2 is a side elevation of the block with a portion appearing in vertical cross section, being a view taken as indicated by line 2—2 on Figure 1;

25 Figure 3 is a transverse detailed sectional view taken as indicated by line 3—3 on Figure 2 showing coupler tips engaged in the block;

Figure 4 is a side elevation of one of the coupler units removed from the block;

30 Figure 5 is a fragmentary side elevation of the block illustrating a form of clip that may be used to secure the cover to the block;

Figure 6 is a vertical cross sectional view taken as indicated by line 6—6 on Figure 5;

35 Figure 7 is a view similar to Figure 6 showing another form of clip;

Figure 8 is a fragmentary longitudinal sectional view illustrating another form of coupler means that may be embodied in the block; and,

40 Figure 9 is a vertical detailed sectional view taken as indicated by line 9—9 on Figure 8 illustrating the manner in which the tips are engaged in the couplers.

The connector block of the invention illustrated in Figures 1 to 7 inclusive may be said to comprise generally a body 10, a plurality of multiple coupler units 11 in the body 10, pins or tips 12 for the conductors C adapted to be engaged in the coupler units 11, and means 13 for removably retaining the coupler units in the body 10.

45 55 The block body 10 serves to support and house

the multiple coupler units 11. In the preferred construction, the body 10 is a simple, one piece element, although the invention contemplates the fabrication of the body from two or more sections if desired. The body 10 may be designed to carry a multiplicity of the coupler units 11 in any selected or required spaced relation. In the drawing the body 10 is an elongate one piece member constructed to contain a row or series of longitudinally spaced units 11. The body 10 illustrated in the drawing is rectangular in transverse cross section having a flat bottom, vertical side faces, and a horizontal top surface. The opposite ends of the body 10 are provided with projecting attaching ears 14 to facilitate the attachment of the block to a support. Openings 15 are provided in the ears 14 to receive attaching screws or the like. Tubular rivets or bushings 16 line the openings 15 and have radial annular flanges 17 on their ends. The openings 15 are counter-bored at the under sides of the ears 14 to receive the lower flanges 17.

Longitudinally spaced sockets or pockets 18 are provided in the body 10 to contain the coupler units 11. The pockets 18 enter what I have termed the upper side of the block body 10 and extend downwardly a substantial distance. The pockets 18 have vertical side and end walls, and the bottom walls of the pockets are curved and concave. The several pockets 18 are identical in size and shape, and may be equally spaced along the body 10. The longitudinal spacing of the pockets 18 may be varied but it is preferred to space the pockets substantial distances apart so that the individual wires leading to the coupler units 11 are easily accessible. If desired, vertical weight reducing openings 19 may be provided in the body webs occurring between the pockets 18. The side walls of the body 10 have horizontal openings 20 communicating with the pockets 18. In accordance with the invention there is a plurality of openings 20 communicating with each side or end of each pocket 18. The corresponding openings 20 in the opposite walls of the body 10 are aligned and preferably of the same diameter. In the particular case illustrated there are three spaced openings 20 communicating with each end of each pocket 18, it being understood that there may be any required number of openings. The openings 20 are spaced and located so that the lowermost openings 20 communicate with the lower parts of the pockets 18 and the uppermost openings communicate with the upper parts of the pockets.

The block body described above is preferably formed of a dielectric material. In practice the body 10 may be formed of a phenolic resin, Bakelite, hard rubber, porcelain or the equivalent. It will be noted that the body 10 may be readily cast in the form of a one piece unit. In some applications of the invention a long strip having the pockets 18, openings 20, etc., may be initially formed and then cut into lengths or units having a selected number of pockets 18 and the end portions of these units may then be machined to have the attaching ears 14.

The coupler units 11 serve to electrically and mechanically connect the wires of the pairs or groups of wires that are brought into the block. The coupler units 11 are arranged in the pockets 18 and are retained in the pockets by the means 13 to be hereinafter described. If desired, a coupler unit 18 may be provided in each pocket, but in certain applications the units may be arranged in selected pockets as the installation

requires. The coupler units 11 are preferably identical.

The coupler units 11 are vertically disposed generally rectangular element proportioned to be readily introduced into the upper ends of the pockets. As best illustrated in Figure 3 of the drawing, the units 11 have clearance with the end walls of the pockets 18. The coupler units 11 are constructed of relatively thin resilient material such as beryllium copper and may be plated with silver, or the like. The individual coupler units 11 may be formed from a single length or blank of stock, but in the case illustrated, each unit embodies two mating or complementary sections 21 to facilitate the manufacture. Each section 21 has spaced horizontal grooves pressed or formed in its inner side. In the construction illustrated, three grooves are formed in each section and the grooves of the associated sections oppose and communicate with one another to constitute elongate horizontal openings 22. The openings 22 extend between the opposite vertical edges of the units 11 and are cylindrical and uniform in diameter. The upper and lower openings 22 of the units 11 are positioned so that the upper and lower edges of the sections 21 engage or abut at the respective upper and lower walls of the openings. This is shown at 23 in the drawing. By reason of this construction, the upper and lower extremities of the coupler units 11 are cylindrically convexed. As best illustrated in Figure 2 of the drawing, the convex lower edges of the units 11 are adapted to substantially conform to the concave bottom walls of the pockets 18. This engagement of the lower edges of the units 11 with the concave bottom walls of the pockets assists in centralizing the units in the pockets. The units 11 are proportioned so that their upper extremities lie in or slightly below the plane of the upper surface of the body 10 when the lower extremities of the units rest on the bottom walls of the pockets. The coupler units 11 are constructed so that their openings 22 are in registration with the corresponding openings 20 in the side walls of the body 10.

The portions 24 of the coupler unit sections 21 between the end openings 22 and the intermediate openings 22 are flat and substantially vertical. The opposing surfaces of these flat portions 24 are in engagement and lie in the same vertical planes as the abutting edges 23 of the sections 21. The invention provides means for connecting the straight portions 24 so that there is substantially uniform resistance offered to the insertion of the tips 12 into the several openings 22 and so that the units 11 offer uniform or identical resistance to withdrawal of the tips. These means comprise securing members 25 connecting the straight portions 24. In practice the members 25 may be rivets. Two or more horizontally spaced rivets 25 connect each pair of straight portions 24. The rivets 25 lie in horizontal planes that are closer to the upper and lower openings 22 than they are to the intermediate openings 22. This is clearly shown in Figures 2, 3 and 4. The rivets 25 being in adjacent relation to the end openings 22, increase the gripping action of the units 11 at the end openings, thus compensating for the fact that there is nothing connecting the sections 21 at the upper and lower extremities of the units 11.

The coupler units 11 are provided with lock or latch openings for releasably latching the coupler tips 12. Openings 26 are provided in the sections 21 to communicate with the intermediate openings 22 midway between the vertical extremities

of the units. The openings 26 are substantially rectangular and have active latch walls lying in planes normal to the longitudinal axes of the openings 22. The openings 26 are elongated vertically to extend into the flat vertical portions 24. Similar openings 27 are provided in the upper and lower edge portions of the units 11 to communicate with or partially intersect the upper and lower openings 22. The openings 27 are of the same width as the openings 26 and have vertical walls lying in the same planes as the vertical walls of the openings 26.

The coupler pins or tips 12 are secured to the wires or conductors C that are to be engaged and connected in the block. The tips 12 are simple, inexpensive parts and are preferably identical. The outer portions of the tips 12 are in the nature of sockets 29 for receiving the exposed end portions of the conductors. The sockets 29 may be crimped on to the conductors C to be securely, mechanically and electrically connected therewith. If desired, the tips 12 may be soldered to the conductors C instead of being crimped thereon. The tips have portions 30 adapted to be received in the side openings 20 of the block body 10 with sliding or working clearance. The parts 31 of the tips which extend inwardly from the portions 30 are reduced in diameter and are proportioned to be snugly or frictionally engaged in the openings 22 of the coupler units 11. Heads 32 are provided on the inner ends of the tips 12. The heads 32 are adapted to snap or engage in the openings 26 and 27 to releasably lock the tips in the coupler units 11. The heads 32 have rearwardly and laterally divergent surfaces terminating at rather abrupt shoulders 33. The tapered or rounded heads 32 are readily introduced into the openings 20 and their tapering or rounded configuration permits them to be forced into the openings 22 of the resilient coupler units 11. As best illustrated in Figure 3 of the drawing, the heads 32 have a maximum diameter considerably greater than the normal diameter of the openings 22 so that the units 11 are expended or flexed when the tips 12 are introduced into the units.

The tips 12 are pressed into the units 11 until the heads 32 suddenly snap or engage in the openings 26 and 27. The abrupt shoulders 33 at the bases of the heads 32 cooperate with the walls of the openings 26 and 27 to dependably latch the tips in the coupler units. The heads 32 may have flat end faces that engage when the shoulders 33 cooperate with the walls of the openings 26 and 27. The electrical connection between the pairs of aligned tips 12 is maintained by the cooperation of the walls of the openings 22 with the tip parts 31 and the engagement of the heads with one another is not depended upon to preserve the electrical connection between the tips. Shoulders 34 occur where the tip portions 30 join the reduced tip parts 31 and the shoulders 34 are engageable with the edges of the units 11 to limit the inward travel of the tips. The cooperation of the shoulders 34 with the edges of the units 11 prevents the tips 12 from displacing one another when the tips are engaged in the block.

The means 13 serves to cover the upper ends of the pockets 18 to protect the coupler units 11 and to retain the units in the block. The means 13 is in the nature of a closure or cover means and includes a cover plate 35. The cover plate 35 is an elongate rectangular part preferably of dielectric material. The upper side of the body 10 has a longitudinal groove 36 for receiving the cover plate 35.

Clip means is provided to removably retain the cover plate 35 on the body 10. A clip 37 is provided on each end of the body 10. The clips 37 are formed of spring steel, beryllium copper or the like. The clips 37 have feet 38 arranged against the upper sides of the ears 14 and the feet are provided with openings for receiving the bushings 16. The upper flanges 17 of the bushings 16 hold the feet 38 against the upper sides of the ears 14. The clips 37 extend upwardly from the feet 38 and are provided at their upper ends with lugs or tongues 39 for cooperating with the cover plate 35. The tongues 39 bear downwardly and inwardly against the upper surface of the cover plate 35 to dependably hold the plate on the body 10.

Figures 5 and 6 illustrate an alternative form of clip 40 for detachably securing the cover plate 35 on the body 10. The clip 40 is in the nature of a strip of flexible resilient material of substantially inverted U shape. The wings or end parts 41 of the clip 40 are in downwardly and inwardly convergent relation. The transverse part 42 of the clip 40 slopes downwardly and inwardly from its opposite ends to a detent dimple 43. The side parts 41 are adapted to straddle the upper portion of the block body. Inwardly protruding detent dimples 44 are provided on the side parts 41 and engage in sockets 45 in the sides of the body 10. The dimple 43 on the transverse part 42 is adapted to engage in an opening or socket 46 in the cover plate 35 to restrain the plate against longitudinal movement. Two or more of the clips 40 may be spaced along the body 10 to retain the cover plate 35 on the body. When the plate 35 is arranged in its groove 36, the clips 40 are pressed down over the body 10 so that their side parts 41 are sprung outwardly. The clips are pressed downwardly until the detents 44 snap into the sockets 45, at which time the detent 43 engages the opening 46. The clips 40 dependably hold the cover plate 35 in position but may be easily and quickly removed from the body when it is desired to remove the cover plate.

Figure 7 illustrates another alternative form of clip 47 for removably holding the cover plate 35 on the body 10. The clip 47 is adapted to straddle the upper portion of the body 10 being provided with downturned side parts 48 for extending downwardly at opposite sides of the body. The upper transverse part of the clip 47 has a depressed portion 49 for bearing downwardly against the cover plate 35. Inturned detent parts or fingers 50 are provided on the lower ends of the side parts 48. The fingers 50 are adapted to engage in sockets or slots 51 in the sides of the body 10. Two or more clips 47 may be employed to hold the cover plate 35 in place. The clips 47 are merely pressed down over the body 10 until their fingers 50 snap into the slots 51, at which time the depressed portions 49 come into retaining engagement with the cover plate 35.

In using the connector block described above, the units 11 are readily inserted in the pockets 18 to automatically assume the positions where their openings 22 are aligned with the openings 20. The units 11 may be installed in all of the pockets or in selected pockets as the conditions of use may require. The cover plate 35 is applied to the body 10 and secured in place by the clips 37, 43 or 47, as the case may be.

When it is desired to electrically connect two or more conductors C the tips 12 of the conductors are merely inserted into a selected unit 11.

The tips 12 are passed through the openings 20 and the heads 32 are forced through the openings 22 to finally snap into the openings 26 and 27. As described above, the heads 32 cooperate with the openings 26 and 27 to dependably retain the tips in the units 11. It is to be observed that the several conductors C of a given set or group may all be inserted into one side of the block, or may be inserted into both sides of the block. The gangs or groups of conductors C electrically connected by the coupler units 11, are fully insulated one from the other, and the individual conductors of each group are dependably maintained in electrical connection. If it is desired to provide identifying designations for the several groups or sets of conductors, numerals 65 may be provided on the top of the block body 10 over the spaced vertical rows of openings 20. The numerals 65 are not required and are optional.

When it is desired to disconnect a conductor C its tip 12 is merely pulled from the connector block. The coupler units 11 dependably connect and retain the tips 12, but the tips may be readily withdrawn by applying a sudden pull. It is to be observed that the individual conductors C may be disconnected from the block and that the disconnection of a conductor does not necessitate the removal or disturbing of the other conductors. If it becomes necessary to replace a coupler unit 11, the conductor tips 12 engaged in that particular unit are removed and the cover plate 35 is detached from the body 10 to make the unit 11 accessible. The faulty unit 11 may be readily withdrawn from its pocket 18 and a new or replacement unit 11 may be inserted. In this way the connector block may be easily serviced. It is to be observed that the conductors C may be connected and disconnected without employing tools and that the units 11 may be inserted, withdrawn and replaced without the use of tools.

Figures 8 and 9 of the drawing show the connector block embodying coupler means for electrically and mechanically connecting pairs of straight-through conductors. The body 10 and the means 13 may be the same as in the previously described form of the invention. In the construction illustrated in Figures 8 and 9, one or more tubular resilient coupler units 53 are provided in each pocket 18. The units 53 are elongate tubular members of relatively thin flexible resilient metal. The units 53 are split longitudinally to be expansible radially. Each tubular unit 53 has two spaced circumferentially extending slots or openings 54 intersecting its split. The units 53 are flanged or enlarged at their opposite ends and the enlargements have a greater diameter than the openings 20 so that the units cannot be displaced through the openings.

The coupler units 53 are supported in the pockets 18 to be in alignment with the corresponding openings 20 and to be effectively insulated one from the other. The lowermost units 53 rest on the concave lower walls of the pockets 18. The engagement with the concave bottom walls of the pockets assists in holding the units in alignment with the lowermost openings 20. Spacers 55 of dielectric material are arranged on the upper sides of the lower units 53. The spacers 55 have cylindrically concaved lower faces for conforming to the cylindrical units 53. The coupler units 53 for registering with the intermediate body openings 20 rest on the spacers 55. The upper sides of the spacers 55 are cylindrically concaved to conform to the units 53 and to assist in aligning

the units with the intermediate openings 20. Spacers 56 rest on the intermediate units 53. The spacers 56 may be identical with the spacers 55 having cylindrically concaved upper and lower faces. The uppermost coupler units 53 rest on the spacers 56 to be supported in alignment with the uppermost openings 20. The flanged or enlarged ends of the units 53 protrude from the ends of the spacers 55 and 56 and may have limited clearance with the end walls of the pockets 18. The uppermost units 53 may be engaged by the cover plate 35 or may lie immediately below the cover plate.

The conductors C are provided with tips 57 for engaging or latching in the coupler units 53. The tips 57 have sockets 58 soldered or crimped on the exposed end portions of the conductors C. Parts 59 extend forwardly from the sockets 58 and are proportioned to slidably fit the openings 20 of the body 10. Reduced portions 60 continue forwardly from the parts 59 and have annular enlargements 61 at their ends. The sides or surfaces of the enlargements 61 are curved or tapering. The enlargements 61 are adapted to snap into the openings 54 to releasably secure the tips 57 in the coupler units 53. Tongues 62 extend forwardly from the reduced portions 60. The tongues 62 have flat longitudinal faces 63. The forward parts of the faces 63 are rounded or beveled. The major portions of the faces 63 are pitched rearwardly and laterally so that the opposing tips are releasably latched together by the cooperation of their surfaces 63.

In employing the connector of Figures 8 and 9, the assemblies of superimposed units 53 and spacers 55 and 56 are readily inserted in the pockets 18. These assemblies may be arranged in as many pockets 18 as the particular installation requires. The cover plate 35 is applied to the body 10 to retain the couplers and spacers in the pockets. When a pair of straight-through conductors is to be connected, the tips 57 are merely pushed or pressed into the opposite ends of a selected unit 53. In performing this operation, the two tips 57 are positioned so that the surfaces 63 of their tongues 62 will come into contact. Figure 9 illustrates the manner in which the tips 57 are handled to bring their tongues 62 into proper engagement. When the tips 57 are thrust into the unit 53 the enlargements 61 snap into the openings 54 to dependably latch or retain the tips in the positions where the surfaces 63 are in contact to maintain electrical contact between the conductors C. The unit 53 closely engages about the portions 60 and tongues 62, and forms an electrical coupling between the two tips 57. In the form of the invention illustrated in Figures 8 and 9, a multiplicity of pairs of in-line or straight-through conductors C may be readily connected and each pair of conductors is maintained electrically separate from each other pair.

If desired, tips 12 such as illustrated in Figure 3 may be used in the connector block of Figures 8 and 9. When the tips 12 are used in conjunction with the device of Figures 8 and 9, the openings 54 are omitted from the units 53 and openings similar to the openings 26 are provided in the units 53 midway between their ends to receive the heads 32.

Having described only typical forms of the invention, I do not wish to be limited to the specific details herein set forth, but wish to reserve to myself any variations or modifications that may appear to those skilled in the art or fall within the scope of the following claims.

I claim:

1. A device for connecting a plurality of electrical conductors having tips provided with axially facing shoulders, the device comprising a body of dielectric material having spaced pockets entering it from the top and having spaced sets of spaced openings entering it from its opposite sides for the reception of said tips and extending to the pockets, there being at least one set of openings extending to any given pocket, a coupler introduced into each pocket from its upper end, each coupler comprising two resilient sections connected together in face to face relation, the opposing faces of the sections having registering grooves forming openings which register with the first named openings for frictionally receiving said tips, and axially facing shoulders on the walls of said openings in the couplers for cooperating with said shoulders on the tips to resist withdrawal of the tips.

2. A connector block for connecting electrical conductors having tips, said block including a body having a vertical pocket entering its upper end and having spaced horizontal openings extending through it from one side to the other and intersecting said pocket, and a coupler unit inserted into the pocket from its upper end and supported on the bottom wall of the pocket, the coupler unit comprising two resilient parts connected in face to face relation, the opposing faces of said parts having opposing grooves which register to form openings for receiving said tips, the supporting engagement of said bottom wall of the pocket with the coupler unit serving to position the coupler unit where the second named openings are aligned with said horizontal openings.

3. A device for facilitating the connection of electrical conductors having tips comprising a body of dielectric material having spaced pockets entering its upper end and having spaced sets of spaced openings entering it from at least one side and extending to the pockets for receiving said tips, there being at least one set of openings extending to any given pocket, resilient coupling units contained in the pockets for receiving said tips, a cover on the upper end of the body for closing the outer ends of the pockets, and spring

clips on the body for engaging the end portions of the cover to removably retain the cover on the body.

- 5 4. A connector block for electrically and mechanically connecting conductors having tips provided with shoulders comprising an elongate body having longitudinally spaced pockets entering its upper end and having longitudinally spaced sets of vertically spaced openings in its opposite sides 10 communicating with the pockets for receiving said conductor tips, coupling units removably inserted in the pockets and having sets of vertically spaced openings communicating with the first named openings, for receiving said conductor tips, spaced axially facing shoulders on the walls of the second named openings for latching with the shoulders of said tips, a cover for closing the upper ends of the pockets, and means for retaining the cover on the body.
- 20 5. A connector for facilitating the connecting of electrical conductors comprising a body having a pocket extending downwardly from its upper end and having vertically spaced openings extending from its opposite sides to the pocket for receiving said conductors, a coupler removably inserted in the pocket and supported on the bottom wall thereof, and having spaced openings communicating with the first named openings for receiving said conductors, the engagement of 25 the coupler with the bottom wall of the pocket serving to position the coupler where its openings register with said first named openings, and means for covering the pocket and retaining the coupler therein.
- 30 6. A connector block for facilitating the connecting of electrical conductors including a body having spaced substantially vertical pockets entering its upper end and spaced substantially horizontal openings extending from its opposite sides to the pockets for receiving said conductors, couplers removably inserted downwardly into the pockets and resting on the bottom walls thereof, each coupler having spaced openings communicating with the said openings of the body for receiving said conductors, and a removable cover 35 plate on the body closing the upper ends of the pockets.

DOUGLAS K. ROLLOW.
